UNITED STATES PATENT OFFICE.

MORTIMER M. YOUNG, OF BALTIMORE, MARYLAND.

DESIGN FOR AN ENVELOPE.

SPECIFICATION forming part of Design No. 19,799, dated April 29, 1890.

Application filed October 19, 1889. Serial No. 327,577. Term of patent 7 years.

To all whom it may concern:

Be it known that I, MORTIMER M. YOUNG, a citizen of the United States, residing at Baltimore, in the State of Maryland, have invented and produced a new and useful Design for Envelopes, of which the following is a specification, reference being had therein to the accompanying drawings.

Figure 1 is an obverse view with the flap extended. Fig. 2 is a reverse view of Fig. 1.

The leading feature of the design consists in having the reverse side and a portion of the obverse side along a portion of one of its edges of a color contrasting with that of the remainder of the obverse side.

A is the obverse side, B the reverse side, and C the flap. The entire reverse side and a portion, as C', 1, 2, or 3, of the obverse side along a portion of one of the marginal edges are of a solid color contrasting with that of the remaining portion of the obverse side.

What I claim as new is—

The design for an envelope, substantially as herein shown and described.

In testimony whereof I affix my signature in presence of two witnesses.

MORTIMER M. YOUNG.

Witnesses:

E. B. STOCKING,
HEATH SUTHERLAND.
